[57] **CLAIM**

The ornamental design for a trash bag hanger, as shown and described.

DESCRIPTION

FIG. 1 is a right side perspective from above of a trash bag hanger showing my new design; and
FIG. 2 is a left side perspective view from below thereof.

The broken line showing of a supporting wastecan and a supported trash bag is for illustrative purposes only and forms no part of the claimed design.

U.S. Patent

Apr. 25, 1989

D300,804

FIG. 1

FIG. 2
